UNITED STATES PATENT OFFICE

BENJAMIN H. WELLS, OF SEATTLE, WASHINGTON, ASSIGNOR TO HEATER GLOVE COMPANY, OF SEATTLE, WASHINGTON, A CORPORATION

AVIATOR'S HELMET

Application filed July 2, 1929. Serial No. 375,369.

This invention relates to improvements in aviators' helmets.

The primary object of this invention is the provision of headgear or helmets constructed in a novel relation at the top thereof so as to permit the smooth form-fitting of the same upon the top of the head of the wearer.

A further object of this invention is the provision of an improved aviator's helmet having a novel three-piece top construction which will permit of the same to be efficiently formed to fit the top of the head of the wearer; the forehead, cheeks, neck, and beneath the chin of the wearer in a conforming relation which will prevent the flutter of parts thereof, and wind from entering the helmet.

Other objects and advantages of this invention will be apparent during the course of the following detailed description.

In the accompanying drawings, forming a part of this specification, and wherein similar reference characters designate corresponding parts throughout the several views,

Figure 1 is a front perspective view of the improved helmet.

Figure 2 is a rear perspective view of the helmet.

Figure 3 is a perspective view of the helmet with the chin straps connected.

Figure 4 is a bottom plan view of the chin strap connection of the helmet.

Figure 5 is a transverse sectional view taken through the helmet looking forwardly.

Figures 6 and 7 are sectional views taken substantially on their respective line in Figure 5.

Figure 8 is a plan view of a reinforcing detail of the helmet.

Figure 9 is a developed view of the parts of the helmet as cut in conformity to patterns and prior to the relative assemblage thereof.

In the drawings, wherein for the purpose of illustration is shown only a preferred embodiment of the invention, the letter A may generally designate the helmet, or the outer

covering of a helmet, and it is intended that the same shall be lined if found advisable to suit the character of use of the same. The helmet consists of a top portion extending over the top of the head of the wearer and over the forehead and the back of the neck of the wearer consisting of a center piece 15 and adjacent right and left panels 16 and 17; the same being connected together. Right and left sides 18 and 19 are provided, 50 for connection with the panel sections 16 and 17 respectively to complete the helmet.

In the conventional helmet there is a center seam running along the top and from front to back of the helmet, and because of this and the fact that the top of the helmet is ordinarily not of snug form fitting structure, there is apt to be looseness of some kind, which permits the wind to enter, to the discomfort of the wearer.

In Figure 9 are diagrammatically shown the helmet portions 15 to 19 inclusive in their plane positions, as they are cut from the pattern. The central strip 15 is elongated, symmetrical at each side of its longitudinal axis, 65 and narrower at the forehead and neck ends 21 and 22 respectively, than at the intermediate portion 23; the opposite side edges being convexly arcuated. The forehead end 21 has the end edges sloping at 25 in a convergent relation, to a point which is along the center line of the helmet, to provide, in combination with the bias cut edges 33 of the strips 16 and 17, a tab at the forehead portion of the helmet, as shown in Figures 70 1, 3, 5, and 6, which the aviator may grasp in pulling the helmet in snug relation on the head or to facilitate its removal.

The top panels 16 and 17 at opposite sides of the top center section 15 are of general 85 crescent-shaped formation, having convex edges 28 adapted to be connected by stitching, or in any approved relation against or in overlapping relation with the convex adjacent margins of the top portion 15. The 90

opposite side edge of each of the panels 16 and 17, shown at 30, is concaved. The said panels 16 and 17 are widest intermediate their ends, and at the forehead engaging ends 31 thereof, the same have the bias cut edges 33 adapted to slope in a flush relation with the converging edges 25 of the center portion 15, to produce the peaked or tab effect at the forehead of the helmet, as shown in Figures 1, 3 and 5 of the drawings.

Referring to the side pieces 18 and 19, the same are of half circular formation provided with tapered shanks 40 and 41 respectively for extension beneath the chin of the wearer. The convex edges 44 thereof are adapted to be marginally connected along the concave edges 30 of the panel strips 16 and 17.

With the parts connected as above mentioned, there are provided four seam lines extending from front to rear along the top of the helmet, held by stitching 46, and eliminating the seam along the plane of symmetry of the helmet. With the parts connected in this manner, there is provided the peaked portion which dips at the forehead part of the helmet. The margins of the connected helmet parts may be suitably finished with edging 50, with an additional reinforcing edging 51 at this peaked forehead portion of the helmet, as shown in Figure 1. On the rear of the helmet, preferably externally on the side pieces 18 and 19 thereof are provided the usual goggle strap supporting extensions 55, of any approved type.

Exteriorly on the chin abutting shanks 40 and 41 there are provided parts 70 and 71 of a connecting strap; the part 70 being an apertured strap having an end 73 extending through an opening or slot 74 in the shank 40, transversely therein, and secured thereto as by stitching; the apertured strap 70 of course having a series of apertures therealong and the same extending beyond the end margin of the shank 40, as shown in Figure 1. The part 71 is similarly connected exteriorly upon the shank 41, with an end extending through a transverse slot 75 in the said shank 41, and stitched therein; the strap 71 being relatively short and having a buckle 77 at the end thereof for connection with the strap 70, in a manner which is apparent. If desired, a loop 80 may be provided exteriorly upon the shank 40, transversely thereacross, through which the strap 70 is threaded, as shown in Figure 2.

The making of the shank 40 longer than the shank 41 enables the former to be doubled in an overlapping relation beneath the latter, with the helmet upon the head of a wearer, in the relation shown in Figure 3, and the fastener parts 70 and 71 buckled into connected relation below the chin of the wearer. It is thus apparent that there will be no discomfort or irritation to the skin below the chin of the wearer, due to the fastener or

coupling holding the helmet snug fitting about the face and upon the head of the wearer, inasmuch as the overlapping of the shank parts prevents the fastening devices from coming into contact with the wearer's chin. A diamond shaped reinforcing piece 60 is stitched inside of the helmet at the forehead covering part thereof, across the adjacent ends of the top pieces 15, 16 and 17 and this reinforcing piece 60, together with the reinforcing edging 51 secured to the strips 15, 16, and 17, and the side pieces 18 and 19, enables the tab to be effectively used in pulling the helmet in snug relation on the aviator's head, without danger of tearing the strips.

Any type of lining may be employed, or the head gear may be made without lining. The lining may be seamless, or the seams made by connecting the edges of the pieces of the lining in a non-overlapping relation, in a manner well known in the art.

All of the parts of the helmet with the exception of the buckle are flexible, and preferably constructed of a good grade of leather, although other materials may be used if desired. The three-piece top construction eliminating the center line seam along the plane of symmetry of the helmet provides a smooth fit upon the head of the wearer, and enables the helmet to be drawn tight about the forehead, cheeks, neck and chin of the wearer.

Various changes in the shape, size, and arrangement of parts may be made to the form of invention herein shown and described, without departing from the spirit of the invention or the scope of the claims.

I claim:

1. A helmet formed of a one piece elongated central strip, opposite side panel strips of crescent-shaped formation, side pieces of half circular formation provided with shank extensions for disposition beneath the chin of the wearer, the opposite side edges of the central strip being convex and the convex edges of the crescent-shaped side panel strips being connected along the convex margins of the central strip to provide a form fitting top construction, said side pieces having convex edges thereof marginally connected to the concave edges of the side panel strips, a reinforcing piece at the front portion of the helmet secured to and extending across the central and side strips, and a reinforcing edging secured at the front of the helmet to said central and side strips and to said reinforcing piece and said side pieces.

2. A helmet formed of a one piece elongated central strip, opposite side panel strips of crescent-shaped formation, side pieces of half circular formation provided with shank extensions for disposition beneath the chin of the wearer, the opposite side edges of the

central strip being convex and the convex edges of the crescent-shaped side panel strips being connected along the convex margins of the central strip to provide a form fitting top construction, the side pieces having convex edges connected to the concave edges of the side panel strips, the fore ends of the central and side panel strips being convergent in a tab forming relation at the forehead of the wearer, a reinforcing piece at the front portion of the helmet secured to and extending across the central and side strips, and a reinforcing edging secured at the front of the helmet to said central and side strips and to said reinforcing piece and said side pieces.
